CLAIM

We claim the ornamental design for a glucose monitoring skin patch, as shown and described.

DESCRIPTION

FIG. 1 is a front right perspective view of a glucose monitoring skin patch in accordance with an embodiment;

FIG. 2 is a top plan view thereof;

FIG. 3 is a bottom plan view thereof;

FIG. 4 is a right side elevation view thereof;

FIG. 5 is a left side elevation view thereof;

FIG. 6 is a front elevation view thereof; and,

FIG. 7 is a rear elevation view thereof.

The broken lines illustrate portions of the glucose monitoring skin patch that form no part of the claimed design.

1 Claim, 4 Drawing Sheets
